UNITED STATES PATENT OFFICE.

OTTO HEINS, OF NEW YORK, N. Y., ASSIGNOR TO BOSCH MAGNETO COMPANY, OF NEW YORK, N. Y., A CORPORATION OF NEW YORK.

MULTIPOLEAR MAGNETO.

1,256,795.

Specification of Letters Patent. Patented Feb. 19, 1918.

Application filed December 24, 1915. Serial No. 68,505.

To all whom it may concern:

Be it known that I, OTTO HEINS, a subject of the Emperor of Germany, residing at and whose post-office address is 336 West 5 88th street, New York city, have invented certain new and useful Improvements in Multipolar Magnetos; and I do hereby declare the following to be a full, clear, and exact description of the invention, such as 10 will enable others skilled in the art to which it appertains to make and use the same.

It was customary heretofore to use bipolar magnetos for igniting the combustible mixtures in internal combustion engines, and 15 this arrangement was satisfactory for the usual four-cycle engines operating at ordinary speed, because the magneto and the gearing therefor operated well at crank shaft speed for four cylinders, and one and 20 one half times crank shaft speed for six cylinders. However, for eight or twelve cylinder engines requiring a speed for a bipolar magneto of two or three times crank shaft speed, and also for high speed engines 25 with four or six cylinders operating at 2500 to 3500 R. P. M., the operation of the gearing is not entirely satisfactory, and the magneto is more likely to miss on account of 30 centrifugal force acting on the interrupter elements.

My invention is directed to a multipolar magneto, that is one in which the armature and field have four or more poles each, and the object of the invention is to provide a 35 magneto of small size capable of being attached to an engine for actuation thereby at comparatively low speed, the arrangement being such that any number of poles may be provided without departing from the general design. Such a magneto may be driven directly by the crank shaft of the engine, thus eliminating magneto gearing, and distributing mechanism for distributing the 40 sparking voltages generated in the secondary winding may be carried by the rotatable member of the magneto and thereby eliminate the distributor gearing also.

In my improved form of magneto, the armature is provided with a plurality of 45 wound poles projecting outwardly from the supporting core, either radially or axially, and the field is made up of a continuous series of alternately-reversed permanent mag-

nets of U-form forming a ring, either around the armature or at the side thereof, with 55 the arms extending inwardly in both cases into coöperation with armature poles. Either the armature or the field may be rotated to generate periodically reversing voltage in the primary winding and a mechanical 60 interrupter is connected to the winding to alter the circuit thereof at appropriate intervals. Preferably, the armature poles are wound with secondary windings also, so that high tension voltage suitable for producing sparks 65 at spark gaps of jump-spark plugs may be generated in the magneto.

In the accompanying drawings illustrating the preferred construction in application to a six pole magneto for a twelve-cylinder four-cycle engine, wherein, as an example, the armature is rotatable and distributor brushes are carried thereby,

Figure 1 is a longitudinal section of the magneto on line 1—1 of Fig. 2;

Fig. 2 is a vertical section on line 2—2 of Fig. 1;

Fig. 3 is an end elevation with the cover of the mechanical interrupter removed; and

Fig. 4 is a wiring diagram.

The armature is fast on a rotatable shaft 1 and is made up of iron laminations bolted together and forming a central core 2 and six radially-disposed outwardly-projecting poles 3. A primary coil 4 and a secondary 85 coil 5 are mounted on each pole.

The field member is stationary and is composed of six permanent magnets of U-form, forming a ring or a continuous series of magnets with their arches 6 extending in 90 circular alignment and their arms 7 and 7' projecting inwardly. These magnets are alternately reversed so that adjacent arms are of the same polarity, 7 representing arms of one polarity, say north, and 7' representing arms of the opposite polarity. The common pole shoes 8 and 8' of soft iron magnetically connect adjacent magnet arms 7 and 7' respectively, and form a series of six poles of alternating polarity throughout and 95 coöperative with the armature poles 3.

In order that the permanent magnets may be stronger magnetically than they would otherwise be, they are shaped for increased length by bending them in wide curves at 105 the extremity of the arches 6 and converg-

ing the arms 7 and 7' in directions substantially radially-inward; and in order to reduce the tendency of the magnetic flux to pass around the field member without entering the armature, the magnets are separated throughout their length and the rear faces of the pole shoes 8 and 8' are recessed between the arms of adjacent magnets. In this way, a multipolar permanent magnet field of much strength is obtained in a small space, while the leakage and diversion of the flux from the armature is reduced.

The side plates 9 of non-magnetic material abut the side faces of all the magnets 15 and are clamped thereto by cross bolts 10. A screw 11 passes through the arch of each magnet and is threaded into an anchor block 12 through which a cross bolt 10 passes. Thus the magnets may be adjusted radially 20 independently of each other by the screws 11, so as to properly adjust the air gap, and afterward the magnets are fixed rigidly with respect to the side plates in adjusted position by tightening the nuts on the cross bolts. 25 The field member is held in position with respect to the armature through the bearings 12 of the shaft, and the magneto is provided with a base or stand 13 depending from the side plates, and with a non-magnetic strap 14 encircling the magnets. The magneto shown in the drawings is about 7 inches in diameter.

The mechanical interrupter for periodically interrupting the circuit of the primary winding 4 comprises the grounded interrupter element 15 and the insulated element 15', mounted for rotation with the armature, and the six equally spaced interrupter cams 16 carried by a normally stationary 40 cam ring 17 provided in the well known way with means (not shown) for adjusting at will its circumferential position to advance or retard the period of ignition. The six primary coils 4 are connected in series, one 45 terminal being connected to the interrupter element 15' and the other terminal being grounded. A coil condenser 18 is mounted fast on the shaft 1, and is connected between the insulated interrupter element and the 50 ground.

The six secondary coils 5 are connected in series and the two insulated terminals are connected respectively to the two spring-pressed distributor brushes 19 and 19', 55 which are carried by the armature for rotation therewith. There is a series of spark-plug distributing contacts 20 and 20' at each end of the armature cooperating with the individual brushes 19 and 19'. These contacts are embedded in plates 21 of insulating material fixed in position to the side plates 9. Each contact is connected to an individual binding post 22.

The magneto shown is intended to be 60 driven directly by the crank shaft of a

twelve cylinder engine, and the twelve binding posts 22 electrically connected to the insulated electrodes of spark plugs in the individual cylinders, as shown in Fig. 4.

As in ordinary bipolar magnetos for ignition systems, an ignition voltage is generated substantially in the period in which the armature poles bridge the spaces between adjacent field poles, the circuit of the primary winding being opened, by the mechanical interrupter at the moment of ignition as a result of engagement between the deflecting interrupter lever 15 and a cam 16. In each rotation of the magneto herein shown, this occurs six times, and accordingly six ignition voltages are generated in the secondary winding. During each period of ignition, the distributing brushes 19 and 19' engage two spark-plug distributing contacts 20 and 20', and the sparks occur simultaneously at the two spark plugs connected in series with the secondary winding at that time, the arrangement being such that the piston of one of the cylinders in which a spark occurs is in the explosion stroke while the piston of the other cylinder is in its exhaust stroke.

It will be apparent from the foregoing that a magneto of the same general design may be provided with 4, 8, 12 or other suitable 95 number of poles, and if desired, the magneto may be driven by the engine through speed change gearing, the number of poles being properly selected to furnish ignition voltages at appropriate periods. It will also be 100 apparent that, if desired, the type of magneto herein disclosed may be associated with distributing mechanism of the ordinary kind driven from the magneto through two to one speed reducing gearing for four-cycle 105 engines.

What I claim is:

1. In a multipolar magneto for electrical ignition systems, a ring field member composed of a continuous series of alternately-reversed permanent magnets of U-form with their arms extending inwardly to common poles of alternating polarity throughout the series, an armature member having a generating winding and a plurality of outwardly-projecting poles constructed and arranged to bridge the spaces between the field poles, and a mechanical interrupter electrically connected to the generating winding, one of said members being rotatable.

2. In a multipolar magnet for electrical ignition systems, a ring field member composed of a continuous series of alternately-reversed permanent magnets of U-form with their arches extending in circular alignment and with their arms extending inwardly to common poles of alternating polarity throughout the series, an armature member surrounded by the field member and having a generating winding and a plurality of 130

radially-disposed poles constructed and arranged to bridge the spaces between the field poles, and a mechanical interrupter electrically connected to the generating winding, 5 one of said members being rotatable.

3. In a multipolar magneto for electrical ignition systems, a stationary ring field member composed of a continuous series of alternately-reversed permanent magnets of 10 U-form with their arms extending to common poles of alternating polarity throughout the series, a rotatable armature having a generating winding and a plurality of poles constructed and arranged to bridge 15 the spaces between the field poles, and a mechanical interrupter electrically connected to the generating winding.

4. In a multipolar magneto for electrical ignition systems, a field member comprising 20 a plurality of pole shoes of alternating polarity and a continuous series of alternately-reversed permanent magnets of U-form magnetically connected to the pole shoes, an armature member embraced by the field 25 member and having a generating winding and a plurality of radially-disposed poles constructed and arranged to bridge the spaces between the field poles, and a mechanical interrupter electrically connected 30 to the generating winding, one of said members being rotatable.

5. In a multipolar magneto for electrical ignition systems, an armature member having a generating winding and a plurality of 35 poles, a ring field member composed of a continuous series of alternately-reversed permanent magnets of U-form shaped for increased length, common pole shoes magnetically connecting the arms of like polarity 40 of adjacent magnets and forming a series cooperative with the armature poles and of alternating polarity throughout, and a mechanical interrupter electrically connected to the generating winding.

45 6. In a multipolar magneto for electrical ignition systems, an armature having a generating winding and a plurality of poles, a ring field composed of a continuous series of alternately-reversed permanent magnets 50 of U-form separated from each other throughout their length, common pole shoes magnetically connecting the arms of like polarity of adjacent magnets and forming a series of poles of alternating polarity cooperative 55 with the armature poles, and a mechanical interrupter electrically connected to the generating winding.

7. In a multipolar magneto for electrical ignition systems, an armature having a generating winding, a field composed of permanent magnets separated from each other throughout their length, common pole shoes magnetically connecting like poles of adjacent magnets and forming a series of poles 85 of alternating polarity cooperative with the

armature poles, and a mechanical interrupter electrically connected to the generating winding, the rear faces of said pole shoes being recessed between the arms of adjacent magnets for the purpose described.

8. In a multipolar magneto for electrical ignition systems, an armature having a generating winding, a field composed of a series of alternately-reversed permanent magnets of U-form shaped for increased length 75 and separated from each other throughout their length, common pole shoes magnetically connecting like poles of adjacent magnets and forming a series of poles of alternating polarity coöperative with the armature poles, and a mechanical interrupter electrically connected to the generating winding, 80 the rear faces of said pole shoes being recessed between the arms of adjacent magnets for the purpose described.

9. In a multipolar magneto for electrical ignition systems, a multipolar armature having poles, a multipolar field composed of permanent magnets, a mechanical interrupter having interrupter elements and coöperative interrupter cams, a primary winding composed of coils mounted on the armature poles and connected in series with each other and with the interrupter elements, and a secondary winding composed of coils also 95 mounted on the poles and connected in series with each other.

10. In a multipolar magneto for electrical ignition systems, a rotatable armature having a plurality of radially-disposed poles, a low tension winding on said poles, a stationary ring field composed of a continuous series of alternately-reversed permanent magnets of U-form shaped for increased length and separated from each other 100 throughout their length, said magnets having their arches extending in circular alignment around the armature and having their arms extending inward, common pole shoes magnetically connecting the arms of like 105 polarity of adjacent magnets and forming a series of poles of alternating polarity cooperative with the armature poles, and a mechanical interrupter having interrupter elements carried by the armature and electrically connected to the terminals of said winding and also having interrupter cams coöperative with the interrupter elements to alter the circuit of the winding at appropriate periods.

11. In a multipolar magneto for electrical ignition systems, an armature member having a generating winding, a ring field member embracing the armature and comprising a plurality of permanent magnets, a mechanical interrupter electrically connected to the generating winding, bearings, one of said members being rotatable in said bearings, and fastening means rigidly fastening the permanent magnets to the bearings.

12. In a multipolar magneto for electrical ignition systems, a rotatable armature having a generating winding, a ring field member embracing the armature and comprising a plurality of permanent magnets of U-form, a mechanical interrupter electrically connected to the generating winding, stationary side plates, and fastening means clamping the magnets between the side plates.
13. In a multipolar magneto for electrical ignition systems, an armature having a generating winding and radially-disposed poles, a ring field member embracing the armature and comprising a plurality of radially-adjustable permanent magnets, a mechanical interrupter electrically connected to the generating winding, side plates fixed in relation to the axis of rotation of the magneto, and fastening means permitting radial adjustment of the magnets and clamping the magnets between the side plates in adjusted position.
14. In a multipolar magneto for electrical ignition systems, a rotatable armature having a generating winding and radially-disposed poles, a ring field member embracing the armature and comprising a plurality of permanent magnets of U-form, a mechanical interrupter electrically connected to the generating winding, stationary side plates, and fastening means comprising for each magnet an anchor block inside the arch of the magnet and connected thereto in radially-adjustable position by a screw, and also comprising a tie rod engaging the anchor block and clamping the side plates in radially-adjusted position against the opposite side faces of the magnets.

In testimony whereof I affix my signature.
OTTO HEINS.
